UNITED STATES PATENT OFFICE.

DAVID OGILVIE, OF CLEVELAND, OHIO.

GOLF-CLUB.

1,203,250.

Specification of Letters Patent.

Patented Oct. 31, 1916.

Application filed May 19, 1916. Serial No. 98,486.

To all whom it may concern:

Be it known that I, DAVID OGILVIE, a subject of Great Britain, residing in Cleveland, county of Cuyahoga, State of Ohio, have invented certain new and useful Improvements in Golf-Clubs, of which the following is a specification.

The invention relates to golf clubs and is particularly adapted for the purpose of 10 picking up a ball out of a "bad lie" so as to throw the ball back on the club and impart to the ball a proper spin so that it will not only rise but also receive the full effective blow of the head of the club.

15 The desired end is realized by providing the club with a projecting portion at the lower part of its front or striking face and this projecting portion can be properly referred to as a "pick up" or lip.

20 As illustrating a specific embodiment of the invention reference is made to the drawing forming a part of this specification and on which drawing—

Figure 1 is a front elevation of a golf club, a portion of the shaft of the club being 25 broken away. Fig. 2 is a plan view of a club with a portion of the shaft broken away. Fig. 3 is a view looking at the bottom of the club and in this figure a portion 30 of the shaft has been broken away. Fig. 4 is an end view of the club with a portion of the shaft broken away; and Fig. 5 is a vertical sectional view taken as on the plane indicated on the line 5—5 of Fig. 1 looking 35 in the direction of the arrows.

It is well known that a golf club comprises a striking head and a shaft generally of wood to which the striking head is secured.

40 The present invention relates to a feature of construction which has been embodied in or applied to the striking head of a golf club.

In the drawing the shaft is designated by 45 A and the striking head by B. The head is preferably made of wood and has the usual lead ballast or weighting material as at C. The striking face of the head is slightly inclined as can be seen from an inspection of 50 Figs. 4 and 5, that is the striking head slopes downwardly and forwardly. At the lower portion of the striking face there is a projection which may be called a pick-up or a pick-up lip. This lip extends along a sub- 55 stantial part of the lower portion of the striking face and projects in front of the

striking face. As at times this pick up or lip may be subjected to an improper blow it is necessary that the lip member be made of a strong, tough and durable material, preferably a composition. Furthermore, as the lip is liable to be subjected to repeated blows and comparatively rough usage it is necessary that the member providing this lip be firmly secured in place in or on the striking head. 60 The member which provides this lip is designated by D and the pick up or lip portion thereof by E. This member D is defined by the broken lines a b c d e and is positioned in place as by a pin F. The member D is 65 also secured in place by being clamped between the brass or other metal shoe G and the wooden portion H of the head by means of the several screws K that serve to draw the shoe forcibly against the underside of 70 the wooden portion H and against the lip member D, thus forcibly maintaining the lip member D in rigid engagement with the wooden portion H of the head. The lip member D is thicker at L—substantially the 75 place where the lip and the lower portion of the striking face merge—and it tapers as it extends into the head and also as it projects from the head.

An inspection of Fig. 5 will make it clear 80 that the underside of the projecting portion of the lip extends forwardly and upwardly and that the upper portion of the lip extends downwardly and forwardly thus imparting to the lip a tapering conformation. If the 85 head were made of metal this lip could be made integral and of the same material as the rest of the head. The lip member D can be glued or cemented to the wood of the head so that the glue or cement will assist 90 in securing and maintaining said lip member in place on the head.

The golf clubs which are known as the brassie and spoon are the clubs on which this pick-up is used, although it can be used on 100 the driver as well and in fact on other forms of clubs, if desired.

The improvements herein set forth are not limited to the precise construction and arrangement shown and described for they 105 may be embodied in various forms and modifications without departing from the spirit and scope of the invention.

What I claim is:

1. A golf club having projecting from the 110 lower portion of its striking face a pick up or lip the lower portion of which lip extends

forwardly and upwardly and the upper portion of which lip extends forwardly and downwardly.

2. A golf club having embodied in or on the striking head thereof a pick up member that is secured in place between the wooden portion of the head and a metal shoe by means of screws which pass through the metal plate and the pick up member into 10 said wooden portion of the head, said pick up member having a lip which projects forwardly beyond the striking face of the head and which lip tapers from the head.

3. A golf club having a wooden head provided with a metal shoe on the underside of 15 said head and with a pick up member of a strong, tough composition, which pick up member is secured in place by screws that pass through the metal shoe, part of which 20 screws pass through the pick up member and all of which screws pass into the wooden

portion of the head, said pick up member having a lip which projects beyond the lower portion of the striking face of the head and tapers therefrom.

4. A golf club having a wooden striking head that is provided with a metal shoe on the underside thereof and having a lip member of a tough strong material, which member is pinned to the wooden head, there also 25 being screws for maintaining the metal shoe in place on the head, part of which screws pass through said pick up member and serve to assist in clamping the pick up member in 30 place in or on the head between the wooden portion thereof and the metal shoe.

This specification signed and witnessed this 15th day of May, A. D. 1916.

DAVID OGILVIE.
